UNITED STATES PATENT OFFICE.

AMOS F. MOREY, OF CHICAGO, ILLINOIS, ASSIGNOR OF ONE-HALF TO
MORTIMER CAHILL, OF SAME PLACE.

BURNER.

SPECIFICATION forming part of Letters Patent No. 643,672, dated February 20, 1900.

Application filed July 31, 1899. Serial No. 725,560. (No model.)

To all whom it may concern:

Be it known that I, AMOS F. MOREY, a citizen of the United States of America, residing at Chicago, in the county of Cook and State 5 of Illinois, have invented certain new and useful Improvements in Burners, of which the following is a specification.

My invention relates to a certain new and improved burner adapted to burn gasolene 10 or a similar light oil, said burner being so constructed as to generate therefrom a sufficient quantity of gas to produce a flame of great heat and when properly applied of great illuminating power.

15 The principal object of the invention is to produce a burner having great generating power and at the same time cheap to manufacture and easy to clean and keep in order.

To such end the invention consists in certain 20 novel characteristics which will be described in connection with the preferred construction in which I have embodied them and will be definitely pointed out in the appended claims.

25 My invention is illustrated in the drawings by means of five figures, of which—

Figure 1 is a side elevation; Fig. 2, a central transverse section in line 2 2 of Fig. 1; Fig. 3, a similar section taken in a plane at 30 right angles to that of Fig. 2; Fig. 4, a horizontal section looking downward upon the plane 4 4 of Fig. 1, and Fig. 5 a detail elevation of an inner part of the burner containing certain generating channels or passages.

35 A is a tubular casing or jacket, into which are screw-threaded a supply-pipe B, a lighting-pipe C, and a needle-valve stem D. The opening α , with which the pipe B connects, extends into the interior of the jacket, and the

40 opening α' , in which the needle-valve stem is screw-threaded, is coned at its inner end and also connects by means of a contracted opening with said interior. A downwardly-extending opening or passage α^2 leads from

45 the passage α' and has screw-threaded in its lower portion a pipe E, terminating in a nozzle e, adapted to direct the gas upward within the burner and provided with an ordinary cleaning-screw e'. The internal bore of the

50 jacket or casing is tapered and a correspondingly-tapered plug F is fitted within it con-

taining a central bore f and an external groove f', doubling back and forth upon itself and leading from the inlet-port α to the needle-valve port α' . The pipe E is preferably screw-threaded partly in the jacket and partly in the plug, so as to hold the latter in place after it has been driven home. The top of the plug is covered by means of a perforated dome G, above which the gas burns, and an incandescing mantle H is suspended over the flame in the manner of the ordinary gas or vapor burners of this sort to produce the required light from the heat of the non-luminous flame. The gas and a sufficient quantity 60 of air are mingled together within the interior bore of the plug, so as to effect a complete and condensed combustion above the dome G. An inverted-dome-shaped shield I is secured to the bottom of the casing, covering the nozzle e and giving to the burner an ornamental and pleasing appearance. A preferably central opening i in the bottom of said dome-shaped cover allows a sufficient quantity of air to pass through to support the combustion. The lighting-pipe C is preferably 65 screw-threaded into an opening α^3 , which after it enters the side of the casing is directed downward and discharges the lighting fluid upon a porous lining J, preferably asbestos felt, upon the inside of the cover or cup I. The lighting-pipe C is intended to be connected with a suitable supply of a proper lighting fluid—as, for instance, alcohol—which may be admitted to the asbestos lining 70 J by means of a valve c.

When the burner is not in operation, the needle-valve is closed, cutting off the passage of the gasolene to the nozzle e. To light the burner, a small quantity of alcohol is admitted, sufficient to saturate the asbestos lining of the cup, and the same is lighted and burned to raise the temperature of the burner to the proper point to generate gas from the gasolene or other liquid employed. This liquid 80 lies within the tortuous passage f' formed by the external channel or groove in the plug and the adjacent walls of the jacket. As soon as the alcohol burns out the needle-valve is opened, permitting the gas to pass out 85 of the nozzle, mingle with the air, rise through the dome G, and fill the interior of the man-

tle H. It is then lighted in the manner of the ordinary burner of this class and heats the mantle to the point of incandescence.

While the specific construction here described is thought by me to be preferable at this time, yet I recognize the possibility of almost unlimited variation in form, arrangement, and construction, and therefore desire not to limit myself to the exact devices or arrangements or combinations thereof herein shown and described as far as the main features of the invention are concerned.

I claim as new and desire to secure by Letters Patent—

15 1. In a generating-burner, the combination with a tubular jacket or casing, of a tubular plug fitted thereto, the meeting surfaces forming between them a generating-passage, and a holding device screw-threaded on one of 20 said parts and bearing upon the other to hold the plug tightly within the casing, substantially as described.

2. In a generating-burner, the combination with a tubular jacket, of a tubular plug fitted 25 within the same, said plug being provided upon its exterior surface with a series of chan-

nels united alternately at top and bottom making in combination with the contiguous wall of the jacket, a continuous tortuous channel between the plug and the jacket, 30 substantially as described.

3. A vapor-generating burner, consisting of a tubular jacket or casing, a tubular plug fitted thereto, the meeting surfaces forming between them a generating-passage, a device 35 for holding the plug tightly within the jacket or casing, a fluid-pipe connecting a part of said generating-passage with a supply, a descending vapor-pipe leading from another part of said passage, a valve controlling said 40 descending vapor-pipe, and a second valve controlling the flow of vapor to the interior of said tubular plug, substantially as described.

In witness whereof I have hereunto set my hand at Chicago, in the county of Cook and 45 State of Illinois, this 24th day of July, A. D. 1899.

AMOS F. MOREY.
